UNITED STATES PATENT OFFICE.

JOHN S. TOWNSEND, OF HARVEY, ILLINOIS, ASSIGNOR TO WHITING CORPORATION,
OF HARVEY, ILLINOIS, A CORPORATION OF ILLINOIS.

LOCOMOTIVE-HANDLING CRANE.

Application filed August 8, 1921. Serial No. 490,507.

To all whom it may concern:

Be it known that I, JOHN S. TOWNSEND, a citizen of the United States, residing at Harvey, in the county of Cook and State 5 of Illinois, have invented a certain new and useful Improvement in Locomotive-Handling Cranes, of which the following is a specification.

This invention relates to traveling cranes 10 for use in locomotive construction and repair shop for lifting a locomotive from one point in a shop to another, frequently over intervening locomotives on the floor of the shop.

15 The object of the invention is to provide a crane for this purpose which will lift the locomotive so high with reference to the crane itself that the crane may operate successfully in a building of very much less head room than is possible in the structures 20 of the prior art, it being obvious that a high building costs more in the first place and requires more heat every day to, in cold weather, keep it at a proper temperature.

25 The invention consists in a crane structure capable of attaining the foregoing objects, which can be comparatively easily and cheaply made, which is satisfactory and efficient in use and is not liable to get out 30 of order. The invention further consists in many features and details of construction which will be hereafter more fully set forth in the specification and claims.

Referring to the drawings in which like 35 numerals represent the same parts throughout the several views,

Figure 1 is a side elevation of a crane embodying the features of this invention, showing a locomotive raised to its extreme high 40 position with reference to the crane.

Figure 2 is a detail end view taken on the line 2—2 of Figure 5.

Figure 3 is a detail end view taken on the line 3—3, of Figure 2.

45 Figure 4 is a detail end view taken on the line 4—4 of Figure 5.

Figure 5 is a detail end view taken from the left hand end of Figure 1 showing the method of connecting the front end of 50 a locomotive to the crane mechanism.

Figure 6 is a similar view on the line 6—6, Figure 1, showing the method of suspending the rear end of the locomotive from the crane mechanism.

55 Figure 7 is a general plan view of the

left hand trolley shown in the upper left hand corner of Figure 1.

Figure 8 is a detail end view of a trolley and its lifting mechanism taken at the upper left hand corner of Figure 1 and also 60 on the line 8—8 of Figure 9.

Figure 9 is an enlarged face view of the trolley itself as shown in the upper left hand corner of Figure 1.

Figure 1 shows conventionally walls 12 65 of a building, having extending along them ledges 14 carrying the conventional form of runway girders 16 supporting the rails 18 on which travel the bridge wheels 20 carrying in conventional form crane bridge girders 22, spaced wide enough apart to allow the locomotive indicated by the boiler 24, the cab 26 and all attached parts to move up in between these girders without interference with the lifting and other crane 75 mechanisms conventionally indicated in Figures 5 and 6.

Running along the top of each bridge girder 22 is a conventional form of trolley track rail 28 on which travel trolley supporting wheels 30—32 carrying one or the other of the trolleys 34 or 36 of Figure 1. These trolleys are identical except that they are reversely positioned and carry different tackle mechanism for engagement with 85 the adjacent locomotive. In order to properly take care of the load carried by the trolleys each trolley is provided at the end nearest to the end of the bridge girder with a single pair of wheels 30, one on each parallel track 28 and at the opposite end toward the center of the crane with two oppositely disposed pairs of wheels 32 also traveling on said rails, the two wheels 32 in each case being required in order to properly sustain the load carried on that end of the trolley in the manner hereafter described. The wheels 32 are preferably mounted on an equalizing truck 38 pivoted 95 conventionally at 39 to the trolley.

As indicated, each trolley has two parallel girders 40 carried directly over the wheels just referred to and spaced apart the width between the crane girders 22. These side girders 40 are connected together at their 105 rear ends, viz, the ends toward the wall of the building by cross members 42 and 44 themselves inter-connected by I-beams 46, all lying in the same horizontal plane as the beams 40 and thus forming a horizontally 110

2
disposed generally U-shaped trolley frame on the base of which the hoisting mechanism comprising the usual hoisting drum 48, motor 50, etc., clearly appearing in Figures 5 7 and 8 is mounted.

In order, however, to not limit the height of travel of the load by the plane of this U-shaped member made up of parts 40, 42, 44, and 46, the side members of the U, viz, 10 the portions of the members 40 which extend to the front of the trolley, viz, towards the center of the crane, are not connected together by cross members lying in the same horizontal plane as the parts just mentioned, 15 but are as clearly shown in Figure 9 connected together by other higher placed cross girders 52 and 54 attached to the upper edges of the girders 40, by any suitable means, thus at the inner end of the trolley 20 greatly increasing the head room into which the locomotive has to be moved.

Each two of these girders 52 and 54 are connected together near their opposite ends, and at proper points for the positioning of 25 the lifting cables, hereafter referred to, by cross members 56 carrying a shaft 58 sustaining rotatable rope or chain carrying sheaves 80 in suitable number as shown in Figure 7. Passing over each winding drum 30 48 and the set of sheaves 80 adjacent to it is a conventional form of rope or cable 82, also passing over a corresponding set of 35 sheaves 86 carried on a tackle block 88 of conventional form adapted in the usual manner for connection, as for instance by a hook 90 to the load to be lifted.

In the construction used in connection with the rear of the locomotive the two opposite hooks 90 carried by the trolley 36 are 40 attached by any suitable means, as for instance the eyes 92 to a cross beam 94 adapted to fit under the rear of the locomotive as shown in Figure 6. In the construction shown in Figure 5 the forward or boiler 45 end 24 of the locomotive is suspended by a suitable cable or strap 96, from the cross beam 98 corresponding in function to beam 94, but this beam 98 being above the main parts of the locomotive instead of below them has to be lifted much higher with reference to the crane than beam 94 does. This 50 is accomplished by detachably securing the ends of the beam 98 on suitable supporting blocks or plates 100 carried on the tackle 55 blocks 88 located adjacent to the ends of that beam. The result of the construction just described is that when the cables 82 controlling this beam 98 are sufficiently wound up by the conventional winding 60 mechanism described, this beam 98 travels right up close to the sheaves 80 as clearly indicated in the upper left hand corner of Figures 1, 2, 3 and 5.

Merely in order to show that the device 65 is, in other respects than those specifically

pointed out, a practical commercial form of trolley, the drawings show the usual driving or rack motor 110 geared in the usual manner to drive the wheels 30. For the same reason the drawings show an auxiliary 70 hoisting mechanism 112 of conventional form adapted to be used as may be necessary in the work, particularly in assembling the beams 94 and 98 preparatory to actual locating them under the locomotive and beginning the lifting operation. 75

In the operation of the device the motors 50 are manipulated to raise and lower the locomotive from the ground to the position shown in Figure 1 and vice versa and the 80 motor 110 is operated to move the crane horizontally.

Having thus described my invention what I claim as new and desire to secure by Letters Patent is:

1. In mechanism of the class described, a trolley for a traveling crane made with a horizontally disposed U-shaped frame suitably supported by wheels, a lifting mechanism carried by the base of the U-shaped frame and a load carrying part extending across the free ends of the U-member substantially higher than the body of the trolley whereby parts to be lifted can pass up into the trolley higher than the horizontal center axis of the trolley. 95

2. In mechanism of the class described, a trolley comprising a horizontally disposed U-shaped frame, lifting mechanism including cables on the central cross bar of the U-shaped frame, cross members connecting the outer ends of the side members of the U-shaped frame located above the general level of the frame so as to allow a part to be lifted and moved up into the frame, and means carried by the cross member over which said lifting cables driven by the lifting means may pass, for the purposes set forth. 105

3. In mechanism of the class described, a locomotive lifting crane consisting of a pair of widely separated bridge members equipped with wheels for movement along a room, a pair of trolleys traveling on the bridge member, lengthwise thereof, the structures of the trolleys at the ends nearest the center of the bridge members being open to allow movable parts to be lifted to pass up into the general frame of the trolleys, sheaves mounted on said last mentioned ends of the trolleys and above the general horizontal axis of the trolleys, lifting mechanisms on the opposite ends of said trolleys, hoisting cables or the like driven by the lifting mechanism passing over said sheaves, a pair of pulley blocks for each set of lifting cables for each trolley, means below one pair of pulley blocks for attaching a beam thereto, such a beam connected thereto for supporting one end of the loco- 110 115 120 125 130

motive, means on the other pair of pulley blocks for supporting a cross beam thereon above the centers of the pulley blocks, a cross beam adapted to be so supported and 5 means for supporting another portion of a locomotive from said last mentioned beam.

4. In mechanism of the class described, a pair of separated sheaves for load carrying cables, a set of power driven cables passing over said sheaves, a pulley block for 10 the cables passing over each of said sets of sheaves, means on said pulley blocks for attaching the load below them, means on said pulley blocks for supporting a cross beam between said pulley blocks with its ends supported above the pulley blocks and a detachable beam for that use for the purposes set forth. 15

In witness whereof, I have hereunto subscribed my name.

JOHN S. TOWNSEND.
